Attorney.

UNITED STATES PATENT OFFICE.

WILLARD E. ALLEN, OF TOLEDO, OHIO.

FOUNTAIN BATH-BRUSH.

No. 878,594.

Specification of Letters Patent.

Patented Feb. 11, 1908.

Application filed February 15, 1906. Serial No. 301,136.

To all whom it may concern:

Be it known that I, WILLARD E. ALLEN, a citizen of the United States, resident of Toledo, in the county of Lucas and State of Ohio, have invented a new and useful Improvement in Fountain Bath-Brushes, of which the following is a specification.

My invention relates to a fountain bath brush, and has for its object to provide a simple, inexpensive and convenient device of the kind, the several parts of which are separable for convenience of packing and carriage, and that is adapted for use either with all the parts assembled or with one or more of the parts omitted, the several forms of assemblage being respectively adapted to render the device more convenient of application to different parts of the body, and that is also adapted to the interchangeable use of brush bodies. I accomplish these objects by constructing a brush of a number of separable parts as hereinafter described and illustrated in the drawings, in which

Figure 1 is a view in side elevation partly in section of a brush constructed in accordance with my invention. Fig. 2 is a top view of the same, and Fig. 3 is a perspective view of a brush body, removed from the holder, and with the bail pivotally attached thereto.

In the drawings, 1 is an elliptical brush body adapted to fit within an elliptical cup shaped metallic holder 2, formed of a suitable press drawn blank, in a die adapted to form a rounded back portion 3, and an elliptical rim portion 4 adapted to receive and closely fit around the brush body.

Central of the brush body is provided an orifice 5 adapted to receive the nozzle 6. The nozzle 6 is of a diameter to pass freely through the orifice 5, and is provided at one end with the radially perforated and flanged nozzle cap 7, and at the opposite end with a threaded reduced portion 8 forming a shoulder 9. The threaded reduced portion 8 is provided with a nut 10, having a diameter greater than the orifice 5, and with an internally threaded hose nipple 11, adapted to be run down on the nut 10.

Central of the back of the holder 2 is provided an orifice 12 adapted to receive the threaded portion 8 of the nozzle. The brush body 1 is also provided with the opposite orifices 13 central between its outer and inner faces in diametric alinement transverse its central orifice, and at the nearest oppo-

site points thereto, and with an orifice 14 located at one end at the point farthest from the central orifice. The holder rim 4 is also provided with the side orifices 15 in alinement with the orifices 13, and adapted to register therewith, and with the end orifice 16 adapted to register with the end orifice 14 of the brush body.

In the side orifices of either the brush body or the holder body, there is pivotally mounted the spring bail 17, by the pivots 18 projecting inward in alinement from the end portions of the bail arms 19,—which are normally at a less distance apart than the shortest diameter of the brush body, and require to be sprung apart to insert the pivots into either the orifices 13 of the body or into the orifices 15 of the holder.

The bail 17 is provided with a central angled neck portion 20, from which spring, in a semi-elliptical curve, the arms 19, and central through the neck is provided an internally threaded orifice 21. The arms 19 are of a length and curve to adapt the bail, when the arms are pivoted to the holder, or the brush body to swing from a position arching the holder or the body to a position around one-half the brush body of the holder in which latter position the orifice 21 is in line with the end orifices 14 of the brush body and orifice 16 of the holder, in which position a handle 22, having a socket ferrule 23 provided with a screw 24 projecting axially therefrom at one end which is adapted to be run into the threaded orifice 21 of the holder and the brush body, thereby securely attaching the handle to both the holder and the brush body, and locking the bail, the holder, and the brush body together in position for use.

The several parts thus constructed are adapted to be all assembled together as a fountain brush, having a holder and a handle, as shown in Figs. 1 and 2; or partly assembled as a brush body equipped with a handle, with the holder omitted; or as a brush holder and brush body, with the handle omitted and the bail adapted to loop around the back of the hand holding the brush; or as a brush holder and brush body without the bail or handle; or as a brush having the bail attached as a hand loop as shown in Fig. 3, with the handle and holder omitted; or as a brush body, without the holder, handle, or bail.

In all forms of assemblage of the parts

where the holder is used, before the brush body is inserted into the holder, the nipple 11 is removed from the nozzle 6, and the nut 10 is run out on the threaded portion 8 a short distance to form a shoulder for its outer end portion, which being then inserted through the orifice 12 of the holder as the brush body enters the holder, and the nipple 11 being then run on the threaded portion 8 projecting through the holder until the back of the holder is compressed between the nipple and the nut 10 as shown in Fig. 1, the brush body is then firmly secured in the holder. To the brush body and holder thus assembled, the bail may be added for use as a hand loop by springing the arms 19 outward and inserting the pivots 18 into the side orifices 15; and to the brush body and holder thus assembled, when desired, the handle 22 may be added by moving the bail into position around the end of the holder with the orifice 21 of the neck of the bail in register with the orifice 16 of the holder, in which position the handle may be attached by running the screw through the registered orifices until the end of the handle is compressed on the neck as shown in Figs. 1 and 2.

If it is desirable to use the brush body without the holder, the nozzle 6 may be attached thereto by first removing the nozzle cap 7, and, after inserting the nozzle through the orifice 5 from the back until the nut 10 is shouldered against the back, running the cap 7 on the nozzle again until it is shouldered tightly against the brush body. The nozzle being thus secured, the bail may be attached for use as a hand loop in like manner as described, by inserting the pivots 18 into

the side orifices 13, and to the brush body and the bail thus assembled, the handle 40 may be attached as described for its attachment to the holder, by running the screw 24 through the orifice 21 of the bail neck into the orifice 14 at the end of the brush body.

The parts being assembled in either of the 45 forms described that is most convenient for the special application required, and the nipple 11 being suitably connected by a hose to a water supply under pressure, the brush is in readiness for use, and as required for 50 other special application, parts may be attached or detached. It is apparent that brush bodies of like size and form, but having bristles of different quality may be interchangeably used with the other parts. 55

What I claim to be new is,

In a fountain bath brush, the combination with the brush body 1, having the central orifice 5, of the nozzle 6, provided with the 60 radially perforated flanged cap 7, and the threaded reduced portion 8, a nut 10 adapted to be run on the portion 8, and form a shoulder, the holder 2, having the central orifice 12 to receive the threaded end portion 8 of the nozzle, and a rim portion 4 adapted to receive the brush body, and a nipple 11 adapted to be run on the projecting end portion 8, and compress the back of the holder on the nut. 65

In witness whereof, I have hereunto signed my name in the presence of two subscribing 70 witnesses, this 10th day of February, 1906.

WILLARD E. ALLEN.

In presence of—

GEORGE P. GREENHALGH,

HENRY CAREE.
